METHOD AND MEANS FOR BURNISHING SPHERICAL SEATS

Alfred E. Drissner and Robert Beacom, Cleveland, Ohio, assignors to The National Acme Company, Cleveland, Ohio, a corporation of Ohio

Application January 7, 1939, Serial No. 249,670

15 Claims. (Cl. 29—37)

This invention has to do with the burnishing of spherical surfaces such as ball seats for tie rods, etc., the object of the invention being to provide an improved method, means and tool for the burnishing of such seats during the formation of the blanks on the stock bar and, therefore, before such blanks have been cut from the stock bar or rod from which they are made, and to do this in a very simple, efficient, inexpensive and expeditious manner.

Heretofore, in the manufacture of ball seats for tie rods and similar parts, they have been partly finished on semi-automatic or automatic machines and then the finishing thereof has been completed by a spherical grinding or coining secondary operation and, due to this secondary operation, the manufacturing costs increased because of such subsequent handling, etc.

In other words, it has been the practice to form the blanks from the stock bar or rod by the usual successive operations and then, after they are cut off from the bar, the blanks were submitted to a subsequent operation to burnish them since no practical way has been known to burnish the blanks while still on the bar or rod and there were many objections to this method of procedure. Therefore, the present improvement has been developed as the result of many experiments.

In the present instance, the burnishing tool is shown applied to the tool slide of a multiple spindle screw machine although it may be used with other machines.

In the drawings accompanying and forming a part of this specification, Fig. 1 is a side view of so much of a multiple spindle machine as is deemed necessary to show the present improvement.

Fig. 2 is a detail view of the burnishing tool and a sectional view of the blank.

Fig. 3 is a cross sectional view taken on line 3—3 of Fig. 2.

Fig. 4 is a side view of the mechanism shown in Fig. 1 with the mounting for the burnishing tool shown in section.

Fig. 5 is a cross-sectional view taken on line 5—5 of Fig. 4.

Figs. 6 to 11, inclusive, illustrate the several steps of forming the blank on the stock bar, burnishing the same and cutting the burnished blank from its stock bar by the use of suitable side and end working tools.

Similar characters of reference indicate corresponding parts in the several views.

Before explaining in detail the present im-

provement and mode of operation thereof, we desire to have it understood that the invention is not limited to the details of construction and arrangement of parts which are illustrated in the accompanying drawings since the invention is capable of other embodiments, and that the phraseology which we employ is for the purpose of description and not of limitation.

When this improvement is used, for instance, with a multiple spindle machine, that machine 10 usually consists of a series of rotary work spindles 2 carried by an indexable spindle carrier 3 and through these spindles the stock rods are fed in the usual manner and from these rods the blanks are successively formed by the usual 15 side and end tools.

The machine is also provided with a main sliding tool carrier 4 to which the various end working tools are applied, such as drills, etc., and to which this improved burnishing tool is also 20 applied. Side and top cross slides 5 and 6 carrying side and top tools for forming the blanks and for cutting off the same at the proper time in the usual way are also provided.

In Fig. 6, the blank is shown partly formed 25 by a side working tool and by an end working tool; in Fig. 7, various side and end working tools are utilized further to form the blank; in Fig. 8, the spherical seat of the blank is further formed by an end working tool while, in Fig. 9, 30 this formation of the spherical seat is continued and, at the same time, the cutting-off tool has commenced to sever the blank from the stock bar; Fig. 10 illustrates the burnishing operation 35 while Fig. 11 illustrates the completion of the severing operation of the blank from its bar.

In the present improvement, the burnishing tool is carried by a suitable bracket or holder 7 having anti-friction bearings 8 for supporting a freely rotatable shaft 9 having an enlarged 40 socketed end or head 10 to which the shank 11 of the burnishing tool 12 is secured. This burnishing tool is forced into the rough spherical seat 13 of the stock rod after that spherical seat has first been formed by the end working tools 45 by the forward movement of the tool slide, whereby it will freely rotate with the rotatable stock spindle, it being withdrawn from the spherical seat of the blank as the tool slide moves away from the spindle carrier. Thus, the rotation of 50 the stock spindle rotates the stock rod and the burnishing tool at the same speed as the work so that when the burnishing tool is used on a multiple spindle machine, the burnishing of one piece of work proceeds as the other pieces are 55

successively formed, drilled and bored, the spherical blank having a drilled opening therethrough as at 14.

The burnishing tool 12 which is formed at or 5 attached to the end of the shank 11, the shank being of somewhat smaller diameter than the working surface of the tool, comprises what may be termed a truncated sphere rounded longitudinally of its axis and has a spherical burnishing 10 surface S located at an angle to its shank and to its axis and this burnishing surface S comprises a pair of spaced portions or annular bands 15 and 16 having a relief surface or groove 17 therebetween which allows the metal operated 15 upon by the band 15 or any small particles, to give or slightly flow into this groove which thus acts as a relief surface while the band 16 further burnishes the surface of the work.

This tool is so mounted with relation to the 20 work that the center A of this spherical burnishing surface will approach the spherical surface of the work to be burnished along the axis of the center line of the work spindle, see Fig. 2.

The burnishing tool holder assembly is rigidly 25 mounted on the tool slide and as the tool slide moves toward the work, the spherical surface S contacts the semi-rough area of the work creating sufficient contact friction to revolve the burnishing tool about the axis T of the tool. The 30 angular relation D of the burnishing surface S to the axis T causes this surface S to revolve about its axis T and describe the arc B. The limitation of this arc B is controlled by the angles C and D.

35 The contact of the burnishing surface S on the work at the angle D revolves the burnishing tool faster than at the angle E and the combination of contact pressure plus the angular revolving of the burnishing tool results in a highly burnished surface.

In practice, the burnishing surface S extends 40 over the edge of the hole 14 which permits a smooth spherical surface true to form and by the reason of the formation of the hole prior to the 45 burnishing operation, the blank is completely formed and burnished prior to its being cut off from the bar so that when cut therefrom it is ready for use.

It is to be understood that, by describing in 50 detail herein any particular form, structure or arrangement, it is not intended to limit the invention beyond the terms of the several claims or the requirements of the prior art.

Having thus explained the nature of our said 55 invention and described a way of constructing and using the same, although without attempting to set forth all of the forms in which it may be made, or all of the modes of its use, we claim:

60 1. The method of forming and burnishing a spherically seated blank before it is cut from its stock bar which comprises the operations of rotating the bar in contact with boring and turning instrumentalities to form the blank 65 with a spherical seat, then in contact with a burnishing instrumentality located at an angle to the stock bar, and then in contact with a cutting-off instrumentality on the completion of the burnishing operation.

70 2. The method of forming and burnishing a spherically seated blank before it is cut from its stock bar which comprises the operations of rotating the bar in contact with boring and turning instrumentalities to form the blank with 75 a spherical seat, then in contact with a burnish-

ing instrumentality located at an angle to the stock bar and rotating the same by and with the stock bar, and then in contact with a cutting-off instrumentality on the completion of the 5 burnishing operation.

3. The method of forming and burnishing a spherically seated blank before it is cut from its stock bar which comprises the operations of rotating the bar in contact with boring and turning instrumentalities to form the blank with 10 a spherical seat, then in contact with a burnishing instrumentality having a spherical burnishing surface and so mounted with relation to the work that the center of its spherical burnishing surface will approach the spherical surface of 15 the work along the axis of the center line of the stock bar, and then in contact with a cutting off instrumentality on the completion of the 20 burnishing operation.

4. The method of burnishing a blank prior to 25 its separation from its stock bar and having a spherical seat therein, which consists in forcing a rotatable burnishing tool having a spherical burnishing surface into the spherical seat of the blank while on its stock bar in such manner that the center of its spherical burnishing surface will approach the spherical surface of the work along the axis of the center line of the stock 30 bar, and then subsequently cutting the burnished blank from the bar on the completion of the 35 burnishing operation.

5. The method of burnishing a blank prior to 40 its separation from its stock bar and having a spherical seat therein and an axially bored opening communicating therewith, and which consists in forcing a rotatable burnishing tool having a spherical burnishing surface into the spherical seat of the blank while on its stock bar in such manner that the center of its spherical burnishing surface will approach the spherical 45 surface of the work along the axis of the center line of the stock bar, and then subsequently cutting the burnished blank from the bar on the completion of the 50 burnishing operation.

6. The method of forming a spherically seated 55 blank which comprises the sequential operations of revolving a stock bar successively in contact with means to form a blank with a spherical seat, then in contact with burnishing means having a spherical surface so that the center 60 of the spherical surface of the burnishing means will approach the spherical surface of the work along the axis of the center line of the work, and then in contact with cutting-off means to sever the burnished blank from its bar. 55

7. In a machine of the class described, the combination of a rotary spindle carrying a stock bar, means for forming a blank with a spherical seat from the stock bar, a rotatable burnishing tool having a spherical surface and so mounted that the center of this spherical surface will approach the work along the axis of the center line of the stock bar, means for forcing said burnishing tool into the spherical seat, and means for cutting off the blank from the stock bar after 65 the seat has been burnished.

8. In a machine of the class described, the combination of a rotary spindle carrying a stock bar, means for forming a blank with a spherical seat from the stock bar, a rotatable burnishing 70 tool having a spherical surface and so mounted that the center of this spherical surface will approach the work along the axis of the center line of the stock bar, means for forcing said burnishing tool into the spherical seat, means 75

- for cutting off the blank from the stock bar after the seat has been burnished, and means for rotating the bar and tool, one from the other.
9. In a machine of the class described, the combination of a rotary spindle carrying a stock bar, means for forming a blank with a spherical seat from the stock bar, a sliding tool carrier, a rotatable burnishing tool having a spherical surface and so supported on said sliding tool carrier that the center of the spherical surface of the burnishing tool will approach the spherical surface of the work along the axis of the center line of the work, the rotation of the burnishing tool being effected by the rotation of the stock spindle, and means for cutting off the blank from the stock bar after the seat has been burnished.
10. A burnishing tool shaped as a truncated sphere and having a pair of angularly located annular bands spaced apart to form a relief groove or recess therebetween and so located that the burnishing surface will approach the work at an angle to the axis thereof.
11. A burnishing tool having a spherical surface having a pair of angularly located spaced burnishing bands and so located that the burnishing surface will approach the work at an angle to the axis thereof.
12. A burnishing tool having a spherical surface having a pair of angularly located spaced burnishing bands provided with a relief groove or recess therebetween and so located that the burnishing surface will approach the work at an angle to the axis thereof.
13. A burnishing tool having a burnishing surface located at an angle to the axis of the tool so that the burnishing surface will approach the work at an angle to the axis thereof.
14. A burnishing tool comprising a shank and a burnishing surface comprising one or more annular burnishing bands located at an angle to the axis of the tool so that the burnishing surface will approach the work at an angle to the axis thereof.
15. A burnishing tool comprising supporting means and a spherically formed member having one or more annular burnishing bands located at an angle to the axis of the tool so that the burnishing surface will approach the work at an angle to the axis thereof.
